UNITED STATES PATENT OFFICE.

STEPHEN EVANS ALLEY, OF GLASGOW, SCOTLAND.

AIR-COMPRESSOR.

SPECIFICATION forming part of Letters Patent No. 772,266, dated October 11, 1904.

Application filed January 27, 1904. Serial No. 190,877. (No model.)

To all whom it may concern:

Be it known that I, STEPHEN EVANS ALLEY, a subject of the King of Great Britain, residing at Glasgow, Scotland, have invented certain new and useful Improvements in Air-Compressors, of which the following is a specification.

This invention relates to air or gas compressors, and has for its object the improvements of the distribution in compound or stage air or gas compressors of the differential-piston type.

When in an air or gas compressor a sliding valve is employed operated—as, for instance, by an eccentric—to receive simple harmonic motion for the purpose of controlling the distribution, it is found to operate satisfactorily as far as its regulation of the commencement and completion of the admission to each chamber of the cylinder of the compressor is concerned and also as regards the ending of the discharge of the admitted air at the desired point in the stroke; but the limitations peculiar to slide-valves operated as aforesaid make the regulation by the same valve of the other element of the distribution—that is to say, the control of the commencement of the discharge—a matter of great difficulty—in fact, a practical impossibility—in cases in which it is desired to delay the occurrence of commencement of discharge long enough to secure a good compression. For the purpose of delaying the commencement of discharge under, for example, circumstances such as are above detailed or under any conditions wherein a sliding valve gives a discharge so early that the desired compression is unobtainable with the aid of the sliding valve alone an automatic non-return valve is according to this invention placed in the delivery-passage leading from the sliding valve to the receiver or reservoir to which the compressed air or gas is to be delivered, and this valve is so loaded or controlled that in spite of the premature opening by the sliding valve of the delivery-passage the said non-return valve will cause compression to occur between it and the cylinder to the desired degree before permitting the compressed charge to proceed past it to the receiver or reservoir.

In the accompanying drawings, which illustrate one method of carrying out this invention as applied to a stage air or gas compressor of the differential-piston type, Figure 1 is a plan of the compressor with its valve mechanism. Fig. 2 is vertical section on the line 2 2 of Fig. 1. Fig. 3 is a diagram showing a modified construction of valve mechanism, and Fig. 4 is a diagram showing yet another modified construction of valve mechanism.

Like letters indicate like parts throughout the drawings.

The stage air or gas compressor shown in the drawings has a water-jacketed cylinder A, within which operates a differential or trunk piston B B', which divides the cylinder A into upper and lower compression-chambers A' A'', respectively, and is operated by a crank-shaft E. In compressors of this type the air to be compressed is first admitted to the upper compression-chamber A' and after compression in this chamber is delivered to an intermediate receiver or intercooler, from whence it is allowed to pass to the lower chamber A''. In this chamber it is brought to the required degree of compression and is delivered from thence for use. Extending along one side of the cylinder is a valve-chest C, from which conduits C' C'' communicate with the chambers A' A'', respectively, of the cylinder A. Each of these conduits serves the double purpose of inlet and exhaust for its chamber. The valve-chest is annular in cross-section and contains four coaxial pistons D D' D'' D''', carried by a rod D'', operatively connected to an eccentric E' on the crank-shaft E of the compressor. The upper end of the valve-chest is open to the atmosphere, constituting an inlet by which air may be admitted to the low-compression chamber when the valve is operated to throw the conduit C' into communication with this end of the valve-chest. Below the conduit C' and on the opposite side of the piston D from that which faces the open end of the valve-chest is an exhaust-conduit C''', communicating from the valve-chest to one end of an intercooler or intermediate receiver F. The intercooler F comprises a series of connected gas-tight pipes, preferably water-cooled, and connected at their free end with a

conduit C^4 , communicating from the inter-cooler to the valve-chest at a point situated between the pistons D^2 D^3 . The inlet C^4 is thrown into communication with the chamber A^2 of the cylinder A when the piston D is operated to exhaust the chamber A' of the cylinder, and on the opposite side of the piston D^2 from that on which the inlet C^4 communicates with the valve-chest is situated an exhaust-conduit C^5 , communicating with a reservoir for storing the compressed air, but which is not shown in the drawings. Situated in the exhaust-conduit C^5 is a non-return valve G, controlled by a spring G' , which normally maintains the valve upon its seating G^2 . The outlet-conduit C^3 is similarly controlled by a non-return valve the spring of which is indicated at G^3 .

The operation of this apparatus is as follows: As the piston B B' commences its downstroke in the cylinder A the pistons D D' D² D³, constituting a compound sliding valve, are moved downwardly by the eccentric E'. This causes the piston D to immediately throw the open end of the valve-chest C into communication with the conduit C' of the chamber A' , so that air is admitted to the chamber, and at the same time the conduit C^2 of the chamber A^2 is thrown into communication with the exhaust-conduit C^5 . Presuming the chamber A^2 to be charged, this charge of air is compressed during the downstroke of the piston B B'; but although the conduit C^2 is open for exhaust the charge is prevented from being delivered into the reservoir with which the conduit C^5 communicates, as the spring G' is made of sufficient strength to withstand the pressure exerted upon the valve G by the air compressed between it and the piston B until compression has reached the required degree. When, however, the air has been compressed to a degree slightly in excess of that required, the pressure of the spring G' is overcome by the greater pressure exerted by the air upon the valve, so that the latter is lifted and the air passes it to the reservoir. When the piston B B' has completed half its downstroke, the sliding valve D D' D² D³ commences its upward stroke, and as the piston B B' reaches the limit of its downstroke the valve again assumes the position shown in Fig. 2. From this it will be seen that the commencement and completion of the admission of air to the chamber A' of the cylinder A is accurately timed, but that the commencement of delivery from the chamber A^2 would occur too early if the exhaust-conduit were not controlled by the loaded valve G, although the completion of discharge from this chamber is accurately timed by the return movement of the piston D^2 , which closes the conduit C^2 at the completion of the downstroke of the piston B B'. The cylinder-piston now commences its upstroke and the sliding valve also moves in an upward direction, so that the conduit C'

of the chamber A' is now thrown into communication with the exhaust-conduit C^3 , communicating with the intercooler F. This conduit being, however, controlled by a non-return valve similar to the valve G and loaded by the spring G^3 prevents the delivery of the air which is now compressed between it and the rising piston B until the pressure obtained is sufficient to overcome the force exerted by the spring G^3 , when the valve is forced open and the air passes through to the intercooler. At the same time the piston D² throws the conduit C^2 of the chamber A^2 into communication with the inlet-conduit C^4 from the intercooler F. This allows a charge of compressed air from the intercooler to enter the chamber A^2 of the cylinder A as the piston B rises. When the piston B B' has completed half its upstroke, the direction of movement of the compound sliding valve D D' D² D³ is again reversed, so that the parts once more assume the position shown in Fig. 2 at the completion of the upstroke of the piston B B'. It will be noted that here again the commencement of admission in this case to the chamber A^2 and the completion of this admission and also the completion of the discharge from the chamber A' are accurately timed by the movements of the compound sliding valve; but the commencement of discharge from the chamber A' is made to occur too early by the movement of the sliding valve, which would result in the air being discharged practically without compression if the loaded non-return valve were not inserted in the exhaust-conduit C^5 to control the commencement of the discharge, as described.

Although the non-return valves are shown loaded with a spring, a weight may obviously be employed for the purpose, either secured to or operatively connected with the valve or incorporated in the body of the same.

By constructing the valve-chest C cylindrical in cross-section and employing coaxial pistons therein a very simple and inexpensive form of valve is obtained, as the whole valve-chest may be bored straight through, both ends being left open and the pistons readily inserted. The piston D' constitutes a gas-tight partition dividing the valve-chest into two separate valve-chambers and avoids the extra expense otherwise incurred by boring up to a partition, say, cast in the valve-chest and then boring the partition to form a gas-tight joint with the valve-rod D⁴. The piston D³ serves a similar function and closes the lower end of the valve-chest without the expense otherwise incurred by a gland.

It will be understood that any convenient form of loaded non-return valve may be employed in the discharge-conduits C^3 C^4 , that shown being a simple form by way of example.

The compound sliding valve co-operating with the non-return valves may be variously modified, two modifications being shown in

Figs. 3 and 4. In Fig. 3 the piston D' is dispensed with and a partition shown cast in the valve-chest, although, as described above, this arrangement is more expensive in manufacture. In this figure the piston D⁵ corresponds to the piston D in Fig. 2, the cast partition D⁶, bored to receive a piston-rod D⁹, takes the place of the piston D', and the pistons D⁷ D⁸ correspond to the pistons D² D⁴ of Fig. 2.

10 Fig. 4 shows a compound sliding valve to perform the same functions as those already described, but provided with three pistons D¹⁰ D¹¹ D¹², respectively, only so disposed in relation to the inlet and exhaust conduits of the

15 valve-chest as to constitute a balanced valve.

In the arrangement shown in Fig. 2 the valve is balanced, as the exhaust from either compression-chamber and the admission from the intercooler always take place between two

20 pistons. This arrangement is obviously impossible with three pistons, so that the balancing is effected by closing the ends of the valve-chest, as shown at C⁶ C⁷, Fig. 4, and providing an outlet for an exhaust-conduit C⁸

25 between the upper piston D¹⁰ and the closed end of the valve-chest. The piston D¹⁰ controls the conduit C' of the compression-chamber A' and throws it into communication with the exhaust-conduit C⁸, which communicates

30 with the intercooler, or with an inlet-conduit C⁹, communicating from a source of air-supply with the valve-chest between the piston D¹⁰ and the next piston D¹¹. The piston D¹¹ serves as a gas-tight partition dividing the

35 valve-chest, as before, into two separate valve-chambers, and in the lower valve-chamber is the third piston D¹², controlling the conduit C² of the compression-chamber A². Between the pistons D¹¹ and D¹² an exhaust-conduit C¹⁰

40 from the intercooler enters the valve-chest, and on the opposite side of the piston D¹² a conduit C¹¹ for the chamber A² enters. The rod D¹³, by which the pistons are carried, is enlarged at D¹⁴, so that that portion of the

45 piston D¹² facing the end of the valve-chamber with which the exhaust-conduit C¹¹ communicates is of smaller area than the face of the piston D¹⁰, which is toward the end of the valve-chamber in communication with the

50 exhaust-conduit C⁸.

It will be understood that although both the exhaust-conduits C⁸ C¹¹ are controlled by non-return valves, such as the valve G described with reference to Fig. 2, a body of air is al-

55 ways imprisoned between each of these valves and the pistons D¹⁰ D¹² irrespective of the pistons being in such position as to cover or uncover the conduits C' C², and as the air imprisoned in the conduit C¹¹ and the lower

60 valve-chamber is compressed to a higher degree than that imprisoned in the conduit C⁸ and the upper valve-chamber the reduction of the area of that part of the piston D¹² exposed to this pressure relatively to the area of the piston D¹⁰ and in proportion to this difference

of pressure results in the balancing of the valve.

The sliding valve in Fig. 3 is only partially balanced, as the exhaust from the chamber A' takes place between the piston D⁵ and the partition D⁶ and that from the chamber A² between the same partition D⁶ and the piston D', resulting in a greater pressure being exerted on the latter than on the former.

What I claim as my invention, and desire to 75 secure by Letters Patent, is—

1. In a "stage" gas-compressor the combination of a differential trunk reciprocating piston, a cylinder divided by it into two compression-chambers, an inlet-conduit and an 80 exhaust-conduit both terminating in one of the two compression-chambers, a sliding valve adapted to open and close both conduits, a valve-operating mechanism by which that sliding valve is given simple harmonic motion across the conduits, a fluid-operated valve controlling the exhaust-conduit and situated at a point therein which is farther from the cylinder than is the sliding valve, means for exerting pressure upon the fluid-operated 85 valve sufficient to normally close the exhaust-conduit and so proportioned as to apply to the valve a thrust greater than that which immediately that the sliding valve opens the exhaust-conduit is exerted upon it in such a direction as to tend to open it by the air in compression in that portion of the exhaust-conduit which is between the loaded fluid-operated valve and the piston.

2. In a "stage" gas-compressor the combination of a differential trunk reciprocating piston, a cylinder divided by it into two compression-chambers, an inlet-conduit and an 100 exhaust-conduit both terminating in one of the two compression-chambers, a sliding valve 105 adapted to open and close both conduits, a valve-operating mechanism by which that sliding valve is given simple harmonic motion across the conduits, a fluid-operated valve controlling the exhaust-conduit and situated at a

110 point therein which is farther from the cylinder than is the sliding valve, a loading-spring applied to the fluid-operated valve tending to keep it always in a position in which it closes the conduit and so proportioned as to

115 apply to the valve a thrust greater than that which immediately that the sliding valve opens the exhaust-conduit is exerted upon it in such a direction as to tend to open it by the air in compression in that portion of the exhaust-conduit which is between the loaded fluid-operated valve and the piston.

3. In a "stage" gas-compressor the combination of a differential trunk reciprocating piston, a cylinder divided by it into two compression-chambers, an inlet-conduit and an 120 exhaust-conduit appropriated to and terminating in each of the two compression-chambers, sliding valves adapted to open and close 125 both conduits of each compression-chamber,

a valve-operating mechanism by which the sliding valves are given simple harmonic motion across the conduits, two fluid-operated valves each controlling one of the exhaust-conduits and situated at a point therein which is farther from the cylinder than are the sliding valves, means for exerting pressure upon each of the fluid-operated valves tending to keep each valve always in a position in which it closes the conduit and so proportioned as to apply to the valve a thrust greater than that which immediately that the sliding valves open the exhaust-conduit is exerted upon it in such a direction as to tend to open it by the air in compression in that portion of the exhaust-conduit which is between the loaded fluid-operated valve and the piston.

4. In a "stage" gas-compressor the combination of a differential trunk reciprocating piston, a cylinder divided by it into two compression-chambers, an inlet-conduit and an exhaust-conduit appropriated to and terminating in each of the two compression-chambers, sliding valves adapted to open and close both conduits of each compression-chamber,

a valve-operating mechanism by which the sliding valves are given simple harmonic motion across the conduits, two fluid-operated valves each controlling one of the exhaust-conduits and situated at a point therein which is farther from the cylinder than are the sliding valves, a loading-spring applied to each of the fluid-operated valves tending to keep each valve always in a position in which it closes the conduit and so proportioned as to apply to the valve a thrust greater than that which immediately that the sliding valves open the exhaust-conduit is exerted upon it in such a direction as to tend to open it by the air in compression in that portion of the exhaust-conduit which is between the loaded fluid-operated valve and the piston.

In testimony whereof I have signed my name to this specification in the presence of two subscribing witnesses.

STEPHEN EVANS ALLEY.
